UNITED STATES PATENT OFFICE.

ISRAEL WOLFE, OF GOSHEN, INDIANA.

RAIL-CHAIR.

SPECIFICATION forming part of Letters Patent No. 378,856, dated February 28, 1883.

Application filed May 17, 1887. Serial No. 238,522. (No model.)

To all whom it may concern:

Be it known that I, ISRAEL WOLFE, a citizen of the United States, and a resident of Goshen, in the county of Elkhart and State of Indiana, 5 have invented certain new and useful Improvements in Rail-Chairs; and I do hereby declare that the following is a full, clear, and exact description of the invention, which will enable others skilled in the art to which it app- 10 pertains to make and use the same, reference being had to the accompanying drawings, which form a part of this specification, and in which—

Figure 1 is a perspective view of my improved rail-chair, showing the adjacent ends of two rails secured therein. Fig. 2 is a perspective view of the chair with the removable block removed. Fig. 3 is a detail view of the movable chair. Fig. 4 is a transverse vertical sectional view taken on the plane indicated by line $x\ x$, Fig. 5; and Fig. 5 is a horizontal sectional view taken on the plane indicated by line $y\ y$ in Fig. 4, and looking downward.

The same letters of reference indicate corresponding parts in all the figures.

My invention consists in a new and improved railway-rail chair, which will be hereinafter fully described and claimed.

Referring to the several parts by letter, A indicates the longitudinal base-plate of my improved rail-chair, which is of such a length that its ends rest upon, extend across two adjacent ties, B B, and are firmly secured upon the said ties by the ordinary spikes, C C. Upon one side of the base-plate, upon the upper side thereof, is cast or rigidly secured the stationary cheek-piece or jaw D, the inner longitudinal head, D', of which extends in over the base-plate toward the center of the same, this jaw, or rather its head, being practically square in cross-section.

Upon the lower side of the base-plate A, between its end portions, is cast or secured the downwardly-projecting portion or casting E, which may extend down so that its lowerside rests upon the ground between the ties, and this downward projection or casting E has a mortise or opening, E', formed transversely and centrally through it in a horizontal plane, the top of this opening being only as high as and flush with the lower face of the remainder

of the base-plate, so that the base-plate proper is not weakened by the said opening.

F indicates the movable or adjustable jaw, which is formed with the inwardly-projecting stem or base-piece, G, which is of such size in cross section as to fit snugly within the transverse opening E' in the casting E, and the longitudinal head of the movable jaw is of such a form in cross-section, as shown in Fig. 4, as to fit closely over the base-plate A and the flange of the rail ends.

In operation, the base-plate A having been firmly secured by the spikes C C upon the two adjacent ties, the end of the base-piece G of the movable jaw may be inserted in the opening E' from that side, but without pushing the said block closely in. The meeting ends of the rails H H are then placed on the base-plate A, tilting their ends so that their flanges will clear the heads of the spikes C C, and sliding the bottom flange on one side of the rail ends beneath the head of this stationary jaw D, so that the inner longitudinal part of the said stationary jaw fits closely in against the web of the rail H. The movable jaw is then held in place by the spikes C C.

the rail. The movable jaw is then pushed in position, so that the inner side of its longitudinal head fits closely against that side of the web of the ends of the rails; and when the movable jaw is pushed thus closely in 8c into its operative position a vertical slot, I, in the free end of its base-piece or stem will be just clear of the outer side of the stationary jaw and the base-plate, or rather of the upright registering recess or depression J, cut 85 in the outer side of the said jaw, the base-plate, and also in the same side of the casting E; and in order to lock the adjustable jaw in this operative position a key, K, is slid down through the said vertical slot in that end of 90 the stem or base-piece of the movable jaw fitting partly in the recess J, this key K having the two longitudinal slots K' K' formed in it near each side, as shown, so as to form the side tongues, K² K², at its lower end, and is 95 formed at its upper end with an ordinary head, K³; and the key K is driven down through the slot I as far as possible, the body of the key being made tapering, and when thus driven down its side tongues, K², at its lower end are 100 bent up and around, so as to lock the key in its operative position and prevent the possi-

bility of its working out, thus securely holding the movable jaw in its adjusted operative position.

The inner longitudinal parts of the stationary and adjustable jaws are of such shape in cross-section that they rest both against the stem or web of the ends of the two rails, and also against the under side of the head of the rails and the top of the flanges, as clearly shown in the sectional view, Fig. 4, of the drawings, thus giving great strength and holding the joint very firmly; and as the bottom of the casting E is preferably extended down so as to rest upon the ground, and the rail-joint rests upon two ties instead of one, it will be seen that it is impossible for the joint to sink, or, indeed, for the two ties to sink, and that the joint is made exceedingly solid and firm and not liable to give in any manner.

The inner side of the stationary jaw D is formed or provided with the two stops or projections L L, situated at the ends of the longitudinal head of the said jaw, one of the said stops thus being on each side of the center of the base plate. That side of the flanges of the meeting ends of the rails have the square recesses M M formed in them at a suitable distance from their ends, the length of these recesses being somewhat greater than the length of the stops L L, and when the ends of the rails are placed and secured in operative position within the rail-chair the stops L fit within the recesses M in the rail-flanges, and as the said recesses are longer than the stops a certain amount of movement for expansion and contraction of the rails is provided for, as will be readily understood.

To remove the ends of the rails from the chair, all that is necessary is to straighten out the ends of the key K and drive it by a few

blows from a hammer up out of the slot I, when the movable jaw can be drawn out and the ends of the rails lifted out of the stationary jaw by tilting them so that their flanges will pass over the heads of the spikes C, the ends of the rails being thus drawn outsidewise from the rail-chair.

From the foregoing description, taken in connection with the accompanying drawings, the construction, operation, and advantages of my invention will be readily understood. It will be seen that my improved rail-chair is exceedingly simple and strong in construction and dispenses with all holes in the rails, and all bolts and burrs, and that it forms an exceedingly strong and solid joint for the ends of the rails, while at the same time allowing for their expansion and contraction in heat and cold.

Having thus described my invention, what I claim, and desire to secure by Letters Patent of the United States, is—

In a rail-chair, the combination of a base-plate adapted to be secured to two adjacent ties having the stationary jaws D, formed with notch J, and having the casting E, formed with transverse slot E', with the movable jaw F, having the stem G, formed with transverse slot I, and the key K, fitting in notch J and slot I, and having the tongues K² bent around the stem G from the sides of its lower portion, as shown and set forth.

In testimony that I claim the foregoing as my own I have hereunto affixed my signature in presence of two witnesses.

ISRAEL WOLFE.
